UNITED STATES PATENT OFFICE.

FREDERICK F. GROSSE AND WILLIAM F. LINTZ, OF WAUKEGAN, ILLINOIS,
ASSIGNORS OF ONE-THIRD TO THEODORE H. DURST, OF SAME PLACE.

VALVE.

SPECIFICATION forming part of Letters Patent No. 664,368, dated December 18, 1900.

Application filed October 12, 1897. Serial No. 654,924. (No model.)

To all whom it may concern:

Be it known that we, FREDERICK F. GROSSE and WILLIAM F. LINTZ, of Waukegan, in the county of Lake and State of Illinois, have invented a new and useful Improvement in Valves, of which the following is a description, reference being had to the accompanying drawings, which are a part of this specification.

Our invention has relation to improvements in valves.

The object of the invention is to provide an improved form of valve which shall be simple in construction and of such character as to provide for the ready disassembling of the parts thereof.

With the above primary object in view the invention consists of the devices and parts or their equivalents, as hereinafter more fully set forth.

Figure 1 is a vertical sectional view of the device embodying our invention, and Fig. 2 is an under side view of the collar which surrounds the valve-stem.

Referring to the drawings, the numeral 3 indicates a valve-casing forming an interior valve-chamber and provided with the steam inlet and outlet passages 4 and 5, respectively. Coupled to the upper end of the valve-casing, preferably by a screw-threaded connection, is a valve-stem guide 6. Engaging the threaded bore of this guide is a threaded valve-stem 7, provided at its outer end with a hand-wheel 8. A packing-nut 9 takes onto the upper threaded end of the guide, and a packing 10 is interposed between this nut and the upper extremity of said guide.

The form of valve illustrated in the accompanying drawings consists of a collar 11 and a valve-disk 12, said collar being provided with a depending exteriorly-threaded stem having a recess 13 formed in the lower end thereof. The exterior threads of the depending stem are adapted to engage a threaded recess in the upper surface of the valve-disk, whereby the two parts of the valve are connected. The lower end of the valve-stem fits loosely in the recess 13, formed in the lower end of the collar 11, being held from withdrawal therefrom by the enlarged end 14. The lower end or bottom of disk 12 is provided with a recess 15,

which is filled by a soft-metal packing or plate 16. This packing or plate is held in place by means of a nut 21, turning on a threaded stem 22, depending from the disk 12. This forms the bearing-surface of one side or end of the valve, which surface is adapted to fit the seat 17, and thereby shut off the steam through the outlet-passage 5. The top surface of the collar 11 is also provided with a recess 18, in which is disposed a soft-metal packing or plate 19. The valve-stem guide 6 is provided upon its lower or inner end with an annular bead forming a valve-seat 20. When the valve-stem is turned so as to draw the valve away from the valve-seat 17 and toward the seat 20, the soft-metal packing or plate 19, when the valve is completely opened, will contact with the annular bead or seat 20, and thereby make a steam-tight closure adapted to prevent the escape of steam through the guide 6. When the valve is in this open position, it is obvious that by first removing the hand-wheel 8 the packing-nut 9 can be removed for the purpose of repacking the stem without the necessity of shutting off the steam to the engine.

From the above description it is thought that the operation, construction, and advantages of our invention will be readily understood.

It will be seen that by providing a valve comprising the two sections—viz., the collar 11, provided with a depending exteriorly-threaded stem, having a recess in its lower end, and a valve-disk having a threaded recess in its upper surface adapted to fit the exterior threads of the depending stem, and a valve stem having a head or enlargement at its lower end fitting loosely in the recess in the depending threaded stem of the collar—a means is afforded whereby the threaded valve-stem may be turned independently of the valve, and yet at the same time force or bring the valve to its seat without causing the valve to grind or turn on its seat after contact with said seat and in the operation of being brought firmly against the seat. This function is made possible in our construction by reason of the fact that the frictional bearing-surface of the head or enlargement 14 of the valve-stem is much smaller than the frictional surface of either of the valve-seats 17 or 20, and consequently

the excess friction against said valve-seats will overcome the more limited friction of the head or enlargement 14 and permit the valve-stem to turn, while the valve itself is held 5 stationary against its seat by the excess friction. The construction shown also presents the advantage of permitting the sections of the valve to be readily separated, so as to provide for the disassembling of the parts of the 10 valve and of the removal of the valve-stem, and also for the readily connection of the parts.

We wish it understood that we do not confine our invention to any particular form of 15 valve or valve-casing, as that is immaterial, inasmuch as the novel features of the device are applicable to almost any form of valve, such as gate-valves, &c.

What we claim as our invention is—

20 In a valve, the combination of a valve-casing having inlet and outlet openings and a valve-seat at the mouth of the outlet-opening, a valve-stem guide extending from the casing, the inner end of said guide formed with 25 a valve-seat, a valve comprising a collar and a valve-disk, said collar having a recess in its upper surface and provided on its under surface with a depending exteriorly-threaded

stem; the said stem having the lower end of its bore enlarged in order to form a recess, 30 and said valve-disk provided on its upper surface with a threaded recess adapted to receive the depending stem of the collar, and to be engaged by the threads of said depending stem, and the under surface of said valve-disk provided with a recess and also with a 35 depending threaded stem, a packing fitting the recess in the upper surface of the collar, a packing fitting in the recess on the under side of the valve-disk, a nut engaging the 40 threaded stem of the valve-disk and adapted to be turned against the packing of said valve-disk, and a valve-stem passing through the guide and having a threaded connection therewith and entering the valve-casing, and provided at its inner end with a head or enlargement which fits loosely in the recess of the 45 depending stem of the collar.

In testimony whereof we affix our signatures in presence of two witnesses.

FREDERICK F. GROSSE.
WILLIAM F. LINTZ.
